CLAIM

The ornamental design for a dual compartment bottle, as shown.

DESCRIPTION

FIG. 1 is a perspective view of a dual compartment bottle embodying the new design;

FIG. 2 is a right side elevation view thereof, the left side being a mirror image of the right side as shown;

FIG. 3 is a front elevation view thereof, the rear side being a mirror image of the front side as shown;

FIG. 4 is a top plan view thereof; and

FIG. 5 is a bottom plan view thereof.

FIG. 1

FIG. 2

FIG. 3

FIG. 4

FIG. 5
